UNITED STATES PATENT OFFICE.

EDWARD W. JENKINS, OF CHICAGO, ILLINOIS, ASSIGNOR TO THE McCORMICK HARVESTING MACHINE COMPANY, OF SAME PLACE.

GRAIN-BINDER.

SPECIFICATION forming part of Letters Patent No. 271,074, dated January 23, 1883.

Application filed July 24, 1882. (No model.)

To all whom it may concern:

Be it known that I, EDWARD W. JENKINS, of Chicago, in the county of Cook and State of Illinois, have invented certain new and useful Improvements in Grain-Binders, of which the following is a specification.

My invention relates to that class of automatic binders, whether using cord or wire, in which the binding mechanism is tripped or thrown into action through the instrumentality of the accumulating gavel, so that the sheaves shall be of a practically uniform size and density; and it consists in combining with the shipping-lever of the binder-clutch a packer arranged to mount by the impact of its teeth upon the accumulating gavel, thereby moving said lever; in combining with the grain-receptacle a rotating toothed packer mounted at the head or throat thereof in such manner as to be allowed a bodily-mounting movement, with the impact of its teeth upon the accumulating and compressed gavel, and connections between said packer and the shipping-lever which controls the binder-clutch to cause the engagement or disengagement of said clutch; in combining with the binder-clutch and its shipping-lever, and with the grain-receptacle, a rotary toothed packer carried upon one end of a longitudinally movable support, with its teeth projecting into the throatway of said receptacle, and a lever intermediating between the other end of said support and the free end of the shipping-lever, whereby the latter will be operated by the mounting of the packer upon or behind the accumulating gavel; in combining with a tripping-packer in the throatway of the grain-receptacle a positively-operated compressor or cut-off closing the exit side of said receptacle until started by the tripping of the machine; in an improved clutch consisting of a toothed or ratcheted clutch-half affixed to one of two abutting shafts, and a spring-pressed toothed dog or carrier transversely pivoted to the other, and in the various other combinations and details of construction hereinafter described and claimed.

In the drawings, Figure 1 is a rear sectional elevation of so much of a harvester and binding attachment embodying my invention as

is necessary to a complete understanding of the latter. Fig. 2 is an outer or stubble side view, the harvester being omitted; Figs. 3 and 4, side and front elevations of the packer enlarged; and Figs. 5, 6, 7, and 8, details of the clutch and its shipper enlarged.

A represents the main wheel of the harvester, and B the elevator-frame. A beam, C, supported by or from the outer elevator-struts, or, if convenient, one of the harvester-sills, carries the receiving side of the binder-frame, 55 a portion of which only is shown, the discharge side of said frame being borne upon the outside sill of the harvester, or in any suitable manner.

Properly mounted in the binder-frame, beneath the decking or grain-table, is a constantly-rotating shaft, D, hereinafter called the "driving-shaft," driven from the harvester by chain and sprocket wheel or other gearing. This driving-shaft, in the present instance, does not pass entirely beneath the binder-frame; but as to its inner, and herein the forward, end terminates about midway of the width thereof, and near said end is provided with a fast clutch-half, d, preferably ratchet-toothed to act in one direction only. It also has near this clutch-half a chain or sprocket wheel, d', by which the packer is driven, as will herein-after appear.

In line with the driving-shaft and abutting against its inner end is the binder-shaft E, by which the actual binding devices are driven. Keyed or bolted to the abutting end of this shaft is a tubular head or block, E', which, for the purpose of keeping the two shafts steadily in line at their meeting-point, takes over and serves as a bearing for so much of the inner end of the driving-shaft as projects beyond the clutch-half. To this block, or to ears projecting therefrom, is pivoted by a transverse pivot a carrier or dog, e, having a tooth or lug, e', projecting toward the toothed face of the driving clutch-half, and urged toward the latter by means of a spring, e², seated against a lug upon the block. So long as the carrier is in engagement with the opposing clutch-half the binder-shaft will be locked to and revolve with the driving-shaft, thus actuating

the binding mechanism; but whenever it is disconnected or thrown out of engagement the binder-shaft and mechanism driven thereby will come to a stop and remain at rest. Such disengagement is caused at the end of each complete revolution of the binder-shaft by means of a switch-lever, F, fulcrumed at f to a lug or lugs projecting from the tubular casting or supporting-bar G, one end of said lever normally resting just over and between the carrier and clutch-half, and having an inclined face, f', which is struck by and forces aside an anti-friction roller, or it may be a lug, e³, upon the crown of the carrier as the latter approaches the end of a revolution, thereby swinging said carrier back upon its pivot, away from and out of engagement with the clutch-half, and by the contact between the anti-friction wheel and incline preventing re-engagement so long as the lever is undisturbed.

Bolted fast to the beam C is a standard, H, forming part of, or corresponding in outline with, the grain board or chute—that is, extending upwardly and bending in to a termination 25 immediately beneath the discharge-point of the elevator. In the present instance the body of the standard is formed of two side bars, h, spaced by a block, h', at the head, and by the bolts which hold it to the beam at the foot, so as to afford ledges to said chute and to the inner side of the slotted binding-table I, on either side of the path of the binder-arm, as it moves on its pivot to place the wire or cord around the gavel and carry it into the band-securing devices.

The binding mechanism may be that of the well-known McCormick reciprocating binder, in which case the binder-arm will enter between the ledges from above; or it may be 40 of some other type, with the binder-arm working upon a stationary pivot, either above or beneath the chute. The length and outline of the binding-table will of course depend on the style of said binding mechanism.

K is a rotary fingered wheel, running upon a spindle, k, upon the upper end of a support, k', connected by a link, k², at said end to the standard H, near the head or throatway of the chute. The fingers i of said wheel are preferably pivoted thereto, and have their heels formed as shoes, which travel upon a cam or eccentric, i', arranged in such manner that the fingers, as they are brought up toward the incoming grain, assume and are held in a radial position to strike and force it onward, but when at the limit of their effective action are permitted to fold back upon their pivots, to be readily withdrawn from the stream. The fingers may, however, so far as regards other 55 features of my invention, be rigid with the wheel, and curved or set back from the direction of rotation, as in certain forms of packers or feeders already well known. The support k', bearing the fingered wheel, packer, or feeder, is pivoted at its lower end to one arm, l, of

a lever, L, fulcrumed by means of a rock-shaft, l', in brackets or hangers l² from the beam C, or other convenient part of the framework, the other arm, l³, of said lever being by means of the rock-shaft thrown sufficiently 70 out of line with the first to bring it alongside the free end of the shipping-lever, to which it is coupled by a slot and pin, l⁴, or other connection allowing relative play. To this last-mentioned arm may also be applied an adjustable counter-balance, l⁵, whereby the sensitivity of the device may be determined.

A chain, M, runs from the sprocket-wheel d' over guide-pulleys m, one of which may be on the pivot-pin connecting the lever-arm l' 80 and support k', and the other mounted in a spur or projection, k³, from the latter, up to and over the sprocket-hub of the packer to drive it.

While a gavel is collecting, exit from the 85 grain-receptacle will be closed by the strand of cord or wire stretched across the passage-way, or by a compressor or stop, which at the proper moment will be withdrawn or swung away to allow discharge. It is preferable to 90 relieve the band material, so far as possible, of this duty, and therefore, while any form of compressor or stop adapted to co-act with the other instrumentalities of my invention may be employed, if so desired, I propose to mount 95 at a suitable height above the receptacle and near to the head of the chute a rock-shaft, N, carrying pendent tines N', of sufficient length to block the passage of the grain when down. These tines have at first a straight body, n, 100 which brings them near to the packer or feed-wheel, and forms, in connection with the chute, at that point a throatway for the action of said wheel; then they curve or bulge out at n' to gain space for the gavel and properly shape 105 it. The tines are held closed and swung open at the proper periods by means of a pitman, O, connecting with a crank, o, upon the rock-shaft, and moved by any suitable part of the mechanism driven by the binder-shaft, a toggle, o', being interposed between the end of 110 said pitman and the crank o, in order to increase the oscillation of the shaft, and consequent throw of the tines to open them rapidly and widely.

In the operation of the machine, the grain accumulating in the receptacle and against the tines or other stop gradually backs up in a more or less compact mass against the rotating wheel, which, as its fingers meet with increasing resistance, will mount or roll to retain its position upon the crest or rear side of said mass, pulling with it the support k', and thereby rocking the lever L and depressing the free end of the shipper. This movement of the latter 120 throws its inclined face out of contact with the carrier, which thereupon springs into engagement with the toothed clutch-half on the driving-shaft, and the binder is started, takes the gavel, the tines open for its discharge or re- 125 130

moval, bound or unbound, as the case may be, are immediately reclosed, and the fingered wheel returns to its first position, again setting the shipper to meet and disengage the carrier 5 as the binder-shaft completes its revolution.

When the gavel is to be encircled and completely bound within the above-described receptacle the rotary fingered wheel may serve both as a tripping device and as a packer to 10 consolidate the mass preparatory to binding, and the tines or other stop, as an outside compressor, acting in opposition to the binding-arm until the ends of the band are united and the sheaf is ready to be discharged. If, however, a McCormick reciprocating binder is used, 15 or with some other types which either do not complete or do not commence the binding operation in the receptacle, the office of the rotary fingered wheel may be merely to trip the 20 binding mechanism at the proper moment, notably to pack or compress the gavel for the reception of the band, and the tines will be thrown open as soon as the gavel is grasped for removal.

25 Should the binder be "low level," receiving directly from the harvester-platform without the intervention of an elevator, a spring or equivalent device may be applied to the feed-wheel support or to the shipper to reset the 30 tripping mechanism after the discharge of a gavel or sheaf. Such an instrumentality may also be employed where the wheel is to act as a packer to subject the grain to marked compression.

35 It is obvious that instead of mounting the feed-wheel upon a longitudinally-moving support it may be borne in one arm of a cranked lever; that the form of the clutch may be varied and the shipper and its lever-connections 40 suitably modified to control it; that, according to the nature of the clutch, the binder-shaft may be out of line with the driving-shaft, and that various other changes in matters of detail or of a subordinate character may be made 45 without departing from the principle of my invention.

I claim—

1. In combination with the shipping-lever which controls the binder-clutch, a feeder or 50 packer arranged to mount bodily by the impact of its teeth upon the crest of the accumulating gavel, thereby moving said lever to start the binding mechanism.

2. In combination with the grain-receptacle, 55 a rotating toothed wheel or packer arranged at the head or throat thereof in such manner as to be allowed a bodily-mounting movement with the impact of its teeth upon the crest of the accumulating gavel, and connections between said wheel and the shipping-lever which 60 controls the binder-clutch to cause the engagement of said clutch.

3. In combination with the binder-clutch and its shipping-lever and with the grain-receptacle, a rotary toothed wheel or packer carried 65

upon the end of a longitudinally-movable support, with its teeth projecting into the throatway of said receptacle, and a lever intermediate between the other end of said support and the free end of the shipper, whereby the latter 70 will be operated by the mounting of the wheel upon or behind the accumulating gavel.

4. In combination with the rotary fingered wheel or packer at the head or throatway of the grain-receptacle, the link-guided support 75 upon which it is mounted, the lever-pin jointed by one arm to the lower end of said support, the shipper connected with the other arm of said lever, and the clutch controlled by said shipper. 80

5. In combination with the rotary fingered wheel or packer at the head or throatway of the grain-receptacle, the link-guided support upon which it is mounted, the lever-pin jointed by one arm to the lower end of said support, 85 the adjustable counter-balance upon the other arm of said lever, the shipper connected with said latter arm, and the clutch controlled by the shipper.

6. In combination with the rotary fingered 90 wheel or packer at the head or throatway of the grain-receptacle, the movable support upon which it is mounted, the lever to which the lower end of the support is pivotally connected, the guide-pulleys at said pivotal point, the 95 shipper and clutch controlled by the lever, the sprocket-wheel on the driving-shaft, and the chain running from said sprocket-wheel over the guide-pulleys up to and over the sprocket-hub of the packer. 100

7. The combination of the toothed clutch-half upon the driving-shaft, the transversely-pivoted and spring-seated carrier upon the abutting shaft, the pivoted shipper having an inclined face or switch to throw the carrier out of engagement with the clutch-half, the lever connected to the free arm of said switch by slot and pin, and instrumentalities actuated by the accumulation of the gavel in the receptacle for rocking said lever to disengage the 110 shipper from the carrier.

8. In combination with the rotary fingered wheel or feeder and tripping devices actuated thereby, the rock-shaft and its tines, arranged and operated substantially as hereinbefore set 115 forth.

9. In combination with the rotary fingered wheel or feeder mounted at or near the head of the grain-chute, the overlying rock-shaft provided with cut-off or compressor tines, shaped, 120 substantially as described, to form, in conjunction with the upper part of the chute, a throatway for the action of the wheel while the cut-off is closed to receive and stop the accumulating gavel beyond. 125

10. The rotary fingered wheel or packer having its fingers pivotally secured to the hub, and formed with heel-pieces having two runner-faces, combined with the cam or eccentric, upon the periphery of which the first runner travels 130

during a part of the rotation of the wheel to hold the finger in a radial position, and the second runner during another part to prevent the finger from turning too far back upon its pivot.

11. In combination with the cut-off or compressor rock-shaft and its tines, the pitman by which it is actuated, and the toggle intermediately between the end of said pitman and the crank upon the rock-shaft to increase the throw of the latter.

12. The metal standard H, formed of two spaced side pieces bolted to the beam C, combined with the rotary fingered wheel or packer, substantially as described.

EDWARD W. JENKINS.
